CORD-LOCKING MECHANISM FOR
VENETIAN BLINDS

Walter J. Stuber and John J. Di Ienno, Philadelphia, Pa., assignors to Carey-McFall Co., Philadelphia, Pa., a corporation of Pennsylvania

Application January 27, 1938, Serial No. 187,257

8 Claims. (Cl. 156—17)

This invention relates to slat controlling mechanism for Venetian blinds; and more particularly to means for locking and unlocking the slat elevating and supporting cords or ropes of such structures.

The mechanism forming the subject matter of the present application constitutes an improvement upon the mechanism disclosed in the prior copending application, Serial No. 85,169 filed June 10, 1936, which issued as U. S. Patent No. 2,117,918, dated May 17, 1938; and the present application includes divisible subject matter from said copending application.

The object of the present invention is to provide a simple, inexpensive, highly efficient, positively acting, locking device for the slat elevating and supporting cords or ropes of a Venetian blind.

Referring to the accompanying drawings: Fig. 1 is a face view of the blind structure as viewed from the inside of the window frame at which the Venetian blind is hung;

Fig. 2 is a detached end view of the cord controlling mechanism;

Fig. 3 is a side view of the structure shown in Fig. 2;

Fig. 4 is a sectional elevation taken on the line 4—4, Fig. 2; and

Fig. 5 is a detached perspective view of various elements of the locking mechanism.

As shown in Fig. 1 the Venetian blind includes the usual head rail 1 which in the present case is removably supported by suitable brackets 2 and 3 secured to and at opposite sides respectively of the window frame 4. The head rail 1 is detachably secured in place on the supporting brackets 2 and 3 by latches 5, 5.

Depending from the underside of the head rail 1, adjacent the opposite ends respectively thereof, are blind supporting brackets 6 and 7 in which trunnions 8 and 9 of the slat tilting rail 10 are pivotally mounted. Carried by the bracket 6 is any suitable form of slat tilting mechanism 11 which is operable by a chain or cord 12 for effecting pivotal movement of the tilting rail 10.

Secured to the tilting rail 10, adjacent the opposite ends respectively thereof, are the usual or any suitable form of ladder tapes 13, 13, by which the slats 14, 14 of the Venetian blind are carried in normally flat horizontal planes in vertically spaced relation to each other and through which said slats are caused to tilt, laterally in unison with the tilting of the rail 10, from the horizontal planes shown in Fig. 1 to various angles with respect to the horizontal, in the

usual manner. The ladder tapes 13, 13 are also attached at their lower ends respectively to a bottom rail 15.

Secured to the bottom rail 15, and passing upwardly through suitable openings formed in the slats 14, 14, are the slat elevating and supporting cords 16 and 17. The cords 16 and 17 pass around suitable sheave wheels 18, 19 and 20 which are rotatably mounted in the head rail 1. The slat elevating and supporting cords 16 and 17 pass downwardly from the sheave 20, in the present instance, in a space between the bracket 7 and the bracket 3 in which the locking mechanism 25 forming the subject matter of the present invention is located.

The locking mechanism forming the subject matter of the present invention includes a substantially rectangular housing 26 having open upper and lower ends 27 and 28 respectively. The housing 26 is provided with ears or flanges 29 and 30 by means of which the housing is secured, in the present instance, to the bracket 7 which supports the one end of the tilting rail 10.

In the present instance, the ears 29 and 30 and the brackets 7 are perforated for the reception of securing rivets 31, 31. It will be understood however, that the housing 26 may be secured to the bracket 7, or to any other suitable portion of the blind supporting mechanism, by spot welding or any other suitable means.

The housing 26 comprises side walls 32 and 33 which are connected by a front wall 34, producing together with the bracket 7 a substantially rectangular hollow structure in cross section. The upper end of the housing 26 projects above the bracket 7 into a suitable opening formed in the head rail 1 and provides a mounting for the double grooved rope sheave 20 which is rotatably mounted, between the side walls 32 and 33, on a pin 35 passing through openings 36, 36 formed in said side walls respectively.

Pivotedly mounted on a transversely extending pin 37, which is supported at its opposite ends in the side walls 32 and 33, is a rope gripping catch or latch 38. The latch 38 comprises side wings 39 and 40 which lie adjacent the side walls 32 and 33 respectively. The side wings 39 and 40 are integrally connected to their ends remotely situated with respect to the pivot 37 by a cross plate 41 which forms the outer free end 42 of the latch 38.

The wall 34 of the housing 26, opposite the free end 42 of the latch 38, is apertured at 42. The elevating ropes 16 and 17, after passing around the sheave 20, pass downwardly between 43

the inner face 43 of the wall 34 and the serrated face 44 of the plate 41 which forms the free outer end of the latch 38, and thence, through an opening 45 formed in the outer end 46 of a latch operating element 47.

The latch operating element 47 is in the form of a double arm lever and is pivoted intermediate its opposite ends on a transversely extending pin 48 which is supported at its opposite ends in the side walls 32 and 33 of the housing 26. The short arm 49 of the latch operating lever 47, lies between the outer face 50 of the bracket 7 and the heel ends 51, 51 of the latch 38 and engages said heel of said latch below the pivotal axis of said latch.

In operation, the slat elevating and supporting cords 16 and 17, as shown in Fig. 4, are adapted to be moved vertically in either direction, freely between the apertured wall 34 of the housing 26 and the serrated free end 44 of the latch 38. When the slats have been elevated or lowered to the desired position, swinging of the ropes 16 and 17 to the right, as viewed in Fig. 4, or to the left, as viewed in Fig. 1, will cause said ropes

to bear against the side of the rope opening 45 in the end of the long arm 46 of the latch operating lever 47, and to swing said lever about its pivot 48. The short arm 49 of the lever 47, by reason of its contact with the rear or heel ends 51 of the latch wings 39 and 40 below the pivotal axis 37 of said latch, is caused to swing the latch 38 from its full line position in Fig. 4 to its dotted line position in said figure, whereby the ropes 16 and 17 are pressed outwardly into and through the opening 42 formed in the wall 34 of the housing 26 and jamming said ropes between the upper acute or relatively sharp edge 52 of the opening 42 and the corresponding and cooperating serrations 44 on the outer free end of the latch 38, whereby, upon releasing the ropes 16 and 17 the impetus afforded by the weight of the slats 14 and rail 15 being transmitted through the ropes 16 and 17 to the latch 38, will tend to swing the free end of the latch upwardly to a greater extent and thereby efficiently retain the latch in its rope gripping or snubbing position.

To release the latch 38 a downward pull on the ropes 16 and 17 will first swing the free end of the latch 38 downwardly and subsequently permit the latch 38 to swing about its pivot 37 by gravity, from its dotted line to its full line position shown in Fig. 4, whereupon the ropes 16 and 17 will again be permitted to operate freely between the inner surface 43 of the outer wall 34 of the housing 26 and the serrated face 44 on the outer end of the latch 38.

The operation of the latch 38 into initial contact with the ropes 16 and 17 by the lever 47 under control of the ropes 15 and 16, is positive and eliminates chattering of the latch along the ropes before a positive grip is established therebetween, as has been the case in many Venetian blind structures where no such latch actuating element has been employed.

The pressing of the slat elevating and supporting ropes into and through the opening in the rigid wall of the latch housing causes the ropes to be gripped tightly between the upper acute or relatively sharp upper edge of the opening and the serrated face of the outer free end of the latch.

The several elements of the locking structure, due to their simple construction, can be readily and inexpensively stamped out of sheet metal and

can be quickly assembled by inexpensive labor without sacrificing efficiency of the structure.

We claim:

1. A slat control unit for Venetian blinds comprising a hollow housing including a wall having an opening therein, a slat supporting rope movable vertically in said housing adjacent said wall and across said opening, and a latch pivotally mounted in said housing and adapted to be swung on its pivot by actuation of said rope said latch having a free sharp angle end adjacent said rope opposite said opening and adapted to engage and press said rope outwardly into said opening to force pinch and hold said rope against an acute edge of said opening above said end of said latch under impetus afforded by the weight of the supported slats swinging said latch on its pivot and a second edge of said opening engaging said rope below said end of said latch and forcing said rope inwardly in a sharp reverse bend around said end of said latch under the weight of a portion of the rope depending from said latch end to prevent accidental release of said latch.

2. A slat control unit for Venetian blinds comprising a hollow housing including a wall having an opening therein, a slat supporting rope movable vertically in said housing adjacent said wall and across said opening, and a latch pivotally mounted in said housing and adapted to be swung on its pivot by actuation of said rope said latch having a free sharp angle end provided with a serrated face adjacent said rope opposite said opening and adapted to engage and press said rope outwardly into said opening to force pinch and hold said rope against an acute edge of said opening above said end of said latch under impetus afforded by the weight of the supported slats swinging said latch on its pivot and a second edge of said opening engaging said rope below said end of said latch and forcing said rope inwardly in a sharp reverse bend around said end of said latch under the weight of a portion of the rope depending from said latch end to prevent accidental release of said latch.

3. A slat control unit for Venetian blinds comprising a hollow housing including a wall having an opening therein, a slat supporting rope movable in said housing adjacent said wall and across said opening, a latch pivotally mounted in said housing and having a free end adjacent said rope opposite said opening and adapted to engage and press said rope into said opening to force pinch and hold said rope against an acute edge of said opening under impetus afforded by the weight of the supported slats swinging said latch on its pivot, and means for effecting initial engagement of said free end of said latch with said rope.

4. A slat control unit for Venetian blinds comprising a hollow housing including a wall having an opening therein, a slat supporting rope movable in said housing adjacent said wall and across said opening, a latch pivotally mounted in said housing and having a free end adjacent said rope opposite said opening and adapted to engage and press said rope into said opening to force pinch and hold said rope against an acute edge of said opening under impetus afforded by the weight of the supported slats swinging said latch on its pivot, and means controlled by said rope for effecting initial engagement of said free end of said latch with said rope.

5. A slat control unit for Venetian blinds com-

prising a hollow housing including a wall having an opening therein, a slat supporting rope movable in said housing adjacent said wall and across said opening, a latch pivotally mounted in said housing and having a free end adjacent said rope opposite said opening and adapted to engage and press said rope into said opening to force pinch and hold said rope against an acute edge of said opening under impetus afforded by the weight 5 of the supported slats swinging said latch on its pivot, and a double arm lever pivoted in said housing and having one arm engaging said latch and the second arm engaged by said rope remote to said latch for effecting initial engagement of 10 said free end of said latch with said rope.

6. A slat control unit for Venetian blinds comprising a hollow housing including a wall having an opening therein, a slat supporting rope movable in said housing adjacent said wall and across 15 said opening, a latch pivotally mounted in said housing and having a free end adjacent said rope opposite said opening and adapted to engage and press said rope into said opening to force pinch and hold said rope against an acute edge of said opening under impetus afforded by the weight 20 of the supported slats swinging said latch on its pivot, a heel on said latch, and a double arm lever pivoted in said housing and having one arm adapted to engage said heel and 25 a second arm having an eye adjacent its free end through which said rope passes for effecting initial engagement of said free end of said latch with said rope.

7. A slat control unit for Venetian blinds comprising a slat supporting rope, a fixed rope grip- 30

ping element for and located at one side of said rope, a relatively movable gripping element at the opposite side of the rope in the form of a pivoted latch including laterally spaced side wings connected by a cross plate at the free end of the latch with the rear ends of the side wings having plain edges, a transversely extending pivot for said latch, a double arm lever pivoted on an axis parallel to and located below the latch pivot, said lever comprising one arm engaging 10 the rear edges of the latch wings below the latch pivot and a second arm provided with an eye through which said rope extends below said latch.

8. A slat control unit for Venetian blinds comprising a slat supporting rope, a fixed rope grip- 15

ping element for and located at one side of said rope, a relatively movable gripping element at the opposite side of the rope in the form of a pivoted latch including laterally spaced side wings connected by a cross plate at the free end 20 of the latch with the rear ends of the side wings having plain edges, a transversely extending pivot for said latch, a double arm lever pivoted on an axis parallel to and located below the latch pivot, 25 said lever comprising one arm engaging the plain rear edges of said latch and a second arm provided with an eye through which said rope extends below said latch, said lever being formed of a plate constituting said arms and side wings 30 bent at right angles to said plate and provided with openings through which the pivot of said lever extends.

WALTER J. STUBER.
